[57] CLAIM

The ornamental design for a front panel for an external
drive, as shown and described.

DESCRIPTION

FIG. 1 is a front, left and top perspective view of a front
panel for an external drive showing my new design;

FIG. 2 is a front view thereof;

FIG. 3 is a rear view thereof;

FIG. 4 is a left side elevational view thereof, the right side
view being a mirrored image thereof;

FIG. 5 is a top plan view thereof, the bottom view being
identical thereto; and,

FIG. 6 is a cross-sectional view thereof taken along line
6—6 of FIG. 2 showing the inwardly bending slats.
